UNITED STATES PATENT OFFICE

137,266

DESIGN FOR A COMBINED DISPLAY AND SHIPPING CONTAINER

Paul E. Allen, Skokie, and Edward W. Beatty,
Chicago, Ill.; said Beatty assignor to said Allen

Application June 14, 1943, Serial No. 110,446

Term of patent 14 years

To all whom it may concern:

Be it known that we, Paul E. Allen and Edward W. Beatty, citizens of the United States, residing at Skokie and Chicago, respectively, in the county of Cook and State of Illinois, have invented a new, original, and ornamental Design for a Combined Display and Shipping Container, of which the following is a specification, reference being had to the accompanying drawing, forming a part thereof.

In the drawing:

Figure 1 is a perspective view of a combined

display and shipping container, showing our new design; and

Figure 2 is a front elevational view thereof, on an enlarged scale.

Figure 3 is a top plan view of the article; and

Figure 4 is an end elevational view thereof, on an enlarged scale.

We claim:

The ornamental design for a combined display and shipping container, substantially as shown.

PAUL E. ALLEN.

EDWARD W. BEATTY.
